UNITED STATES PATENT OFFICE.

RANSOM E. OLDS, OF LANSING, MICHIGAN.

DETACHABLE PROPULSION UNIT FOR RAILWAY VEHICLES.

Application filed April 7, 1919. Serial No. 288,418.

To all whom it may concern:

Be it known that I, RANSOM E. OLDS, a citizen of the United States of America, residing at Lansing, in the county of Ingham 5 and State of Michigan, have invented certain new and useful Improvements in Detachable Propulsion Units for Railway Vehicles, of which the following is a specification, reference being had therein to the accompanying drawings.

The invention relates to railway vehicles such as urban and interurban, and it is the object of the invention to obtain a construction which may be economically used where 15 the volume of traffic is not sufficient to maintain a large system.

The invention consists in the construction of a truck unit comprising motor, transmission and track wheels, said unit being 20 quickly attachable to and detachable from the car so as to permit of removal whenever necessary for adjustment or repair.

In the drawings:

Figure 1 is a side elevation, partly in section, of a railway vehicle with my improved unit attached thereto;

Figure 2 is a sectional plan view;

Figure 3 is a side elevation;

Figure 4 is a plan view of the truck unit. 30 In many places at certain periods of the year or for certain hours of the day the volume of traffic on a railway does not justify the maintenance of a central power system. Motor vehicles are frequently used as auxiliaries, but to maintain these continuously in operative condition is a difficult problem. Whenever it is necessary to adjust or repair the mechanism the car necessarily remains 35 idle and therefore a much larger equipment

is required than is ever used at any one time. With the present invention the vehicles can be confined in number to those necessary for handling the traffic while the motor and other mechanism forms a separable 40 unit, a greater number of such units being provided than the number of cars. Thus whenever any repairs are required one unit is detached and is replaced by another unit, this being accomplished in a short time interval.

In detail, A is a frame or platform upon which is mounted a motor B together with a fuel supply tank C, water cooling system D and other needed accessories. The platform A is mounted upon truck axles E 45 through the medium of supporting springs

F, and said axles are coupled by swinging frames G with a jack shaft H mounted in bearings I depending from the platform. Suitable driving connections are arranged 60 between the motor and the axles, and, as shown, the jack shaft H is driven from the motor by the sprocket and chain connection J and the axles E are driven from the jack shaft by sprocket and chain connections K. 65 The necessary radiating surface for cooling of the motor may be arranged beneath the platform, as indicated at L, this being connected with the motor and with the water supply tank D.

The cars M are constructed to receive the truck unit, being preferably provided with doors N at the front which when open will permit the entrance of the upper portion of the unit. The floor of the car is also cut 70 away opposite this entrance and suitable bearings are provided for engagement with the circular portion A' of the platform A so that the latter forms in effect a complementary portion of the floor. The unit is retained and the draft is transmitted to the car body by a front bar O which is detachable for the withdrawal and the insertion of the unit. If desired, the space above the platform of the unit may be separated from 75 the adjoining space within the car by a partition or railing P so that vestibules Q are formed on opposite sides of the unit for the entrance and exit of passengers. When the unit is in place the circular platform thereof 80 engaging the peripheral bearings on the car floor forms in effect a turntable so that the truck is permitted to follow any curvature 85 of the track.

With the construction as described, in use, 90 the truck units may be quickly inserted or removed from the cars, and by providing a sufficient number of such units in excess of those required for continuous operation an inoperative unit can be removed and replaced by another without long delaying the traffic. Furthermore, when the units are 95 disengaged all parts of the mechanism are accessible so that repairs or adjustments can be easily made.

What I claim as my invention is:

1. The combination with a railway car, of a motor truck unit having a detachable engagement with said car, said unit comprising truck axles, a platform, coiled 110 springs mounted upon opposite ends of said axles and carrying said platform, a water

cooled motor mounted upon said platform and a radiator carried below said platform and adapted to receive the water from said motor.

5. 2. The combination with a railway car, of a motor truck unit in engagement therewith, said unit comprising a truck axle, a platform mounted thereon, a water-cooled motor mounted upon said platform, and 10 members providing heat radiating surfaces for the water passing through said engine, said members being located beneath said platform.

3. The combination with a railway car, 15 of a motor truck unit in engagement therewith, said unit comprising truck axles, a platform yieldably mounted thereon, a motor mounted upon said platform, a jack shaft operatively connected to said motor, swinging frames connected to said jack shaft and axles, and driving connections between 20 said jack shaft and each of said axles.

4. The combination with a railway car, of a motor truck unit in engagement there-

with, said unit comprising truck axles, a 25 platform mounted thereabove, springs at the opposite ends of said axles and carrying said platform, a motor mounted upon said platform, bearings depending from said platform, a jack shaft rotatably mounted in said 30 bearings, sprocket and chain connections for driving said jack shaft from said motor, swinging frames connecting said jack shaft to said axles, and sprocket and chain connections for driving each of said axles from 35 said jack shaft.

5. The combination with a railway car having an opening section at its front end, the floor being cut away opposite said opening, of a motor truck unit insertable in said 40 opening and having a platform with a circular portion substantially flush with and forming a swivel connection with the floor, and vestibules at the sides of said unit for admission and exit of passengers. 45

In testimony whereof I affix my signature.

RANSOM E. OLDS.
